UNITED STATES PATENT OFFICE.

WILLIAM BEITNER AND NELSON M. SMITH, OF TRAVERSE CITY, MICHIGAN.

DESIGN FOR A STOVEPIPE.

SPECIFICATION forming part of Design No. 28,146, dated January 11, 1898.

Application filed November 9, 1897. Serial No. 657,982. Term of patent 14 years.

To all whom it may concern:

Be it known that we, WILLIAM BEITNER and NELSON M. SMITH, citizens of the United States, residing at Traverse City, in the county 5 of Grand Traverse, State of Michigan, have invented and produced a new and original Design for a Sheet-Metal Pipe, of which the following is a specification, reference being had to the accompanying drawing, forming 10 part thereof.

The design for sheet-metal pipe is illustrated by a perspective view, such being deemed sufficient for the purpose intended.

As shown in the drawing, the leading or 15 material feature of our design consists of a sheet-metal pipe having a longitudinal groove or corrugation *a* extending from the lower end of the pipe to an intermediate point, an

intersecting annular corrugation *b* near the lower end of the pipe, a series of parallel 20 shorter corrugations *c* branching from one side of the main longitudinal corrugation *a*, and at the upper end of the pipe an outwardly-disposed projection *d*.

Having described our invention, what we 25 claim as new, and desire to secure by Letters Patent, is—

The design for a sheet-metal pipe, as herein shown and described.

In testimony whereof we affix our signatures in presence of two witnesses.

WILLIAM BEITNER.
N. M. SMITH.
